DESIGN.

—o—
C. WHEELER.

WALL PAPER.

No. 17,755.

Patented Sept. 27, 1887.

UNITED STATES PATENT OFFICE.

CANDACE WHEELER, OF NEW YORK, N. Y., ASSIGNOR TO WARREN, LANGE & CO., OF SAME PLACE.

DESIGN FOR WALL-PAPER.

SPECIFICATION forming part of Design No. 17,755, dated September 27, 1887.

Application filed August 26, 1887. Serial No. 247,925. Term of patent 3½ years.

To all whom it may concern:

Be it known that I, CANDACE WHEELER, a citizen of the United States, residing in New York city, in the county and State of New York, have invented a new and original Design for Wall-Paper, of which the following is a specification, reference being had to the accompanying photograph, which forms a part of the same.

10 The invention relates to a design to be stamped upon or worked into surfaces, such as wall-paper or similar articles; and it consists in the novel configuration and grouping of figures herein specifically shown and 15 claimed.

The accompanying photograph is a face view of wall-paper showing my new design.

My design consists of a body part, A, and a border or frieze, B.

20 The body A has a smooth stem-work, different parts of which are intertwined or twisted upon one another like a braid-work. This stem-work is curved more or less regularly, inclosing circular spaces, within which are 25 large circular flowers having concentric rows of radiating leaves. Smaller openings in the stem-work occur between the larger circular

spaces, in which are smaller flowers of the same character, some seen in profile. Here and there upon the stem are supported broad 30 palm-like leaves varying in size, and also small buds.

The border B has an inner margin ornamented with a braid-like work, and an outer margin of a similar character. The middle 35 portion of the border has a continuous curving and intertwining stem work, forming successive circular spaces, each of which is filled with a large circular leaf like the leaves of the body part. The stem also supports small flowers 40 and buds generally overlying the leaves.

What I claim as new, and desire to secure by Letters Patent, is—

1. The design for wall-paper, consisting of the body A, substantially as shown. 45
2. The design for wall-paper, consisting of the border B, substantially as shown.
3. The design for wall-paper, consisting of the body A and the border B, substantially as shown.

CANDACE WHEELER.
